(57) **CLAIM**

The ornamental design for a shoe sole element, as shown and described.

DESCRIPTION

FIG. 1 is a top right front perspective view of the shoe sole element showing a first embodiment of our new design; FIG. 2 is a bottom plan view thereof; FIG. 3 is a rear elevational view thereof; FIG. 4 is a front elevational view thereof; FIG. 5 is a right side elevational view thereof; FIG. 6 is a left side elevational view thereof; and FIG. 7 is a top plan view thereof; FIG. 8 is a top right front perspective view of the shoe sole element showing a second embodiment of our new design; FIG. 9 is a bottom plan view thereof; FIG. 10 is a top rear perspective view thereof; FIG. 11 is a top front perspective view thereof; FIG. 12 is a top right side perspective view thereof; FIG. 13 is a top left side perspective view thereof; and FIG. 14 is a top plan view thereof; FIG. 15 is a top right front perspective view of the shoe sole element showing the first embodiment of our new design seen in FIGS. 1 through 7 in an alternate condition of use; FIG. 16 is a bottom plan view thereof; FIG. 17 is a rear elevational view thereof; FIG. 18 is a front elevational view thereof; FIG. 19 is a right side elevational view thereof; FIG. 20 is a left side elevational view thereof; and FIG. 21 is a top plan view thereof; FIG. 22 is a top right front perspective view of the shoe sole element showing the second embodiment of our new design seen in FIGS. 8 through 14 in an alternate condition of use; FIG. 23 is a bottom plan view thereof; FIG. 24 is a top rear perspective view thereof; FIG. 25 is a top front perspective view thereof; FIG. 26 is a top right side perspective view thereof; FIG. 27 is a top left side perspective view thereof; and FIG. 28 is a top plan view thereof.

The broken lines depict unclaimed portions, as well as the boundaries of the claim, and form no part of the claimed design. The greyed-out uppers seen in FIGS. 15 through 28 depict environmental structure also forming no part of the claimed design.

1 Claim, 28 Drawing Sheets
